[57] **CLAIM**

The ornamental design for a divider for separating stacked articles, as shown.

DESCRIPTION

FIG. 1 is a top plan view of a divider for separating stacked articles embodying my new design;

FIG. 2 is a bottom plan view thereof;

FIG. 3 is a front elevational view thereof, the rear view being substantially a mirror image thereof;

FIG. 4 is a right side elevational view thereof, the left side view being substantially a mirror image thereof; and

FIG. 5 is a top perspective view with a portion of the rear being omitted for convenience of illustration, said portion being a mirror image of the front portion shown.
